UNITED STATES PATENT OFFICE.

FRANK W. ZIMMERMAN, OF AMARILLO, TEXAS.

DRILL.

Application filed September 7, 1921. Serial No. 499,121.

To all whom it may concern:

Be it known that I, FRANK W. ZIMMERMAN, a citizen of the United States, residing at Amarillo, in the county of Potter 5 and State of Texas, have invented a new and useful Drill, of which the following is a specification.

This invention relates to earth boring drills, and it is the primary object of the 10 invention to provide a combined drill and reamer, whereby the drilling and reaming results may be accomplished by a single operation.

A further object of the invention is to 15 provide a drill of this character having an integral reamer forming a part thereof, the reamer having a spiral shoulder forming the cutting edge.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed, may be made within the scope of what is claimed, without departing from the spirit of the invention.

30 Referring to the drawing:—

Figure 1 is a front elevational view of a drill constructed in accordance with the present invention.

Figure 2 is a side elevational view thereof,

35 Figure 3 is a rear elevational view of the drill.

Figure 4 is a sectional view taken on line 4—4 of Figure 2.

Referring to the drawing in detail, the 40 reference character 5 designates the body portion of the drill which has its upper extremity threaded as at 6 to provide means for permitting the drill proper to be positioned within the usual drill bar or stem now 45 in use, in well drilling.

The drill body is preferably flat and is provided with the grooves 7 and 8 formed in opposite sides thereof, which grooves ex-

tend throughout the length of the drill, terminating at a point adjacent the cutting 50 end thereof to provide channel-ways for permitting the material dislodged by the cutting end of the drill to pass upwardly from the opening bored in the ground surface.

55

The reamer 9 forming an important feature of the present invention, comprises an integral body portion formed on the drill adjacent to the upper end thereof, the same being shown as extending laterally from one 60 of the edges of the drill.

This reamer 9 is provided with a spiral shoulder 10 formed at the base thereof, the shoulder constituting the cutting edge of a reamer and is designed to feed the reamer 65 through its work.

As stated, the reamer extends laterally of the drill body at one side thereof, so that when the drill is forced into the ground surface an opening will be formed, the opening 70 having a diameter greater than the diameter of the drill body.

From the foregoing it will be obvious that as the drill is being forced through the ground surface, the well tubing may be applied over the drill, the reamer 9 forming an opening large enough to receive the well tubing which provides the well casing.

Having thus claimed the invention what is claimed as new is:—

80

In a drill, a body portion formed with grooves in the opposed side faces thereof, a reamer formed integral with the body and disposed adjacent to one end thereof, the reamer being formed eccentrically with respect to the body portion, the cutting edge of the reamer being spirally formed and merging with the walls of one of the grooves of the body.

In testimony that I claim the foregoing 90 as my own, I have hereto affixed my signature in the presence of two witnesses.

FRANK W. ZIMMERMAN.

Witnesses:

W. T. DYKEMAN,
H. M. HEFNER.
